UNITED STATES PATENT OFFICE

GEORGE HEGEMAN HART, OF WEST HARTFORD, CONNECTICUT

ELECTRIC SWITCH

Application filed September 28, 1928. Serial No. 308,979.

This invention relates generally to electric switches of the type having a rotatable handle and one or more switch units or poles adapted to be snapped into and out of engagement with suitable terminals or contacts, when the handle is turned.

The aim of the present invention is to provide an improved, simplified, economical and effective arrangement by means of which the handle may be quickly connected to and disconnected from the switch mechanism. My improved arrangement is such that when the handle is in position it is supported to a large extent against rocking or tilting movements.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawings wherein I have shown for illustrative purposes one embodiment which the present invention may take:

Figure 1 is a view taken vertically and centrally through the handle and a portion of the switch mechanism;

Fig. 2 is an exploded view showing in perspective the handle and the various parts carried thereby; and

Fig. 3 is a detail view showing in top plan the actuating member, the driving plate and the spindle, with the stem 32 in section.

In Figure 1 of the accompanying drawings, I have shown so much of a switch of the type illustrated in my copending application, Serial No. 178,434, filed March 25, 1927, as is necessary to make clear one application of the present invention. This showing, of course, is by way of illustration only, it being obvious that the novel features herein described may be applied to and incorporated in switches other than that of the particular kind or type disclosed, and that these features are susceptible of various modifications, changes and adaptations without departing from the spirit of the invention. The switch

unit or pole plates and the base of the switch are not shown in the drawings as they may be of any suitable kind.

The mechanism for throwing the switch unit or units with a snap movement when the handle is turned is shown only in part; a more complete understanding of this construction and the operation thereof may be had by referring to my co-pending application. It may be stated, however, that 10 designates generally an actuating member 55 fixed to a spindle 11; 12, an actuated member connected to the switch unit (not shown) so as to rotate therewith; and 13, 14, elements 60 rotatable with respect to the spindle 11 and the members 10 and 12. The numeral 15 designates a spiral spring, the opposite ends of 65 which are connected to the respective elements 13 and 14. These parts are so associated that when the spindle is initially rotated in one direction, one end of the spring is rotated while the actuated member 12 is holding the other end of the spring against rotation; and when the spindle is initially 70 rotated in the opposite direction, the other end of the spindle is rotated while the opposite end thereof is held against rotation by 75 said actuated member.

In the present illustrative disclosure, the upper end of the spindle is threaded as at 16 80 and is flattened at opposite sides as at 17. The actuating member 10 has a plate portion 18 provided with an opening 19 of substantially the same cross section as the upper end 85 of the spindle so as to closely receive the same. This plate portion 18 also has a lug or ear 20 adapted to cooperate with the elements 13 and 14 as described in my said co-pending application. The member 10 further has a hub or sleeve-like portion 21 90 with a slot 22 at one side. The sleeve-like portion has an end or top wall 23 provided with an internal threaded opening 24. The actuating member 10 is secured in place on the spindle 11 by means of a nut 25. 95

The handle proper is designated by the letter A. It has a bore or well 30 provided with grooves 31 at its opposite sides. Mounted within the well is a connector having a stem 32 provided at its upper end with a head 100

or plate 33 having lugs 34 engaging in the grooves 31, so that the connector is held against rotation with respect to the handle. The handle is normally held against longitudinal movement relative to the stem by a coiled spring 40, the inner end of which abuts against a collar 41. The collar 41 is held in place by a spring ring 42 sprung into an annular groove 43 in the wall of the bore 10 adjacent its open end. The numeral 44 designates a driving plate having an outwardly extending arm with an upturned end 45 engaging in a recess 45a in the pointer portion of the handle. The plate also has 15 an upturned ear 46 engaging in the notch 47 in the handle. Also this plate has an opening 48 for receiving the cylindrical or hub portion 21 of the actuating member 10. There is provided on the plate, a lug 49 20 adapted to engage in the slot 22 of the actuating member. The numeral 50 designates a fibre washer engaging against the driving plate 44 and held in place, together with the driving plate, by ears 51 provided on the 25 collar 41 and bent over as shown in Figure 1.

The stem 32 has a cylindrical bore or recess 55 of slightly larger diameter than the upper end of the spindle 11. This stem has, at its lower end, an external thread 56 which is 30 complementary to the internal thread 24 of the actuating member 10. The portion of the stem, behind—that is, above—the threaded portion 56 is unthreaded and is of somewhat reduced diameter so that when this unthreaded portion engages in the threaded opening 24 it can turn freely therein. The upper endmost convolution of the thread 56 constitutes a shoulder which prevents the connector or stem from being withdrawn from the actuating member.

The internal diameter of the collar 41 is only slightly larger than the diameter of the hub or cylindrical portion 21 so that, when the parts are in place, the collar has a loose 45 bearing on this hub.

When it is desired to connect the handle to the switch, the lower end of the threaded portion 56 is brought into engagement with the opening 24 and the handle is turned so as to 50 screw this threaded portion into the opening. After the threaded portion has a purchase, the handle is pulled outwardly of the stem 32 so that the lug 49 of the driving member will not engage in the groove 22 until 55 after the threaded portion 56 has been entirely screwed through the opening 24. Then the handle is released, whereupon the spring 40 will force the handle down so that the collar 41 will surround the hub 21. When 60 the handle is thus forced down, the lug 49 will engage in the groove 22 so that the actuating member will rotate with the handle when the latter is turned. It will be observed that after the threaded portion 56 has been 65 screwed entirely through the opening 24 the

handle can be turned without turning the actuating member, so long as the handle is pulled out. It will further be observed that when the handle is in place, as shown in Figure 1, the handle is held against tilting or rocking movement owing to the bearings between the stem and the spindle and the stem and collar. To remove the handle it is merely necessary to pull the handle out and then turn it in a direction to unscrew the threaded portion 56 through the opening 24.

As many changes could be made in the above construction and many apparently widely different embodiments of this invention could be made without departing from the scope thereof, it is intended that all matter contained in the above description or shown in the accompanying drawing, shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In an electric switch, a spindle, a member fixed thereto and having an opening provided with an internal thread, a handle having a bore, a stem slidably mounted in said handle and fixed against rotation relative thereto; and a spring, normally urging said stem into said handle, said stem having, on its free end, an external thread complementary to said internal thread, said stem also having an unthreaded portion following and of lesser diameter than said externally threaded portion and adapted to engage in said opening, after said threaded portion has been screwed therethrough.

2. In an electric switch, a spindle, an actuating member fixed thereto and having a hublike portion provided with a threaded opening at one end, a handle having a bore and fixed against rotation relative to said handle, a collar within the open end of said bore and adapted to receive said hublike portion, and a spring held in said bore by said collar and normally urging said stem into said bore, said stem having an external thread and an unthreaded portion following said external thread and adapted to engage in said opening.

3. In an electric switch, a spindle, a bearing member fixed thereto and surrounding the projecting end thereof and having an opening provided with an internal screw thread, a handle, a bearing member carried by the handle for engagement over said first bearing member, a stem slidably mounted in said handle and fixed against rotary movement relative thereto; said stem having an external thread complementary to said in-

ternal thread and an unthreaded portion following said external thread and adapted to engage in said opening.

4. In an electric switch, a spindle, a bearing member fixed thereto and having a threaded opening surrounding said spindle in spaced relation, said member also having a longitudinally extending groove, a handle having a bore, a second bearing member mounted on the bore of the handle adapted to engage about said first bearing member to hold the handle from rocking thereon, a stem slidably mounted in said handle and fixed against rotation relative thereto, and a driving plate fixed to said handle and having a lug adapted to engage in said groove, said stem having an external thread and an unthreaded portion following said external thread and adapted to engage in said opening.
5. In an electric switch, a spindle, a bearing member fixed thereto and having a cylindrical portion provided with a threaded opening at one end, a handle having a bore, a stem slidably mounted in said handle and fixed against rotation relative thereto, said stem having an external thread complementary to the thread of said opening, said stem having an unthreaded portion following said external thread and adapted to engage in said opening, a second bearing member mounted in the handle and surrounding the cylindrical portion of said first bearing member, said handle being adapted when in place to encircle said cylindrical portion.
6. In an electric switch, a spindle, a bearing member fixed thereto and having a cylindrical portion surrounding said spindle and provided with a threaded opening at one end, said cylindrical portion having a groove at one side, a handle having a bore, a stem slidably mounted in said handle and fixed against rotation relative thereto, a driving plate fixed to said handle and having an opening adapted to receive said cylindrical portion and provided with a lug adapted to engage in said groove, said stem having an external thread complementary to the thread of said opening, and an unthreaded portion following said external thread, a second bearing member carried in the handle on said driving plate for engaging about the cylindrical portion of said first bearing member, said handle being adapted when in place to encircle said cylindrical portion.

GEORGE HEGEMAN HART.
